U. S. PATENT OFFICE.

No. 68.

WHOLE No. 1,433.

Tumblers.

CHARLES S. CHAFFEE, OF EAST CAMBRIDGE, MASS.,

ASSIGNOR TO THE BAY STATE GLASS COMPANY, OF SAME PLACE.

Letters Patent of a Design No. 68, dated June 25, 1861.

SPECIFICATION.

TO ALL PERSONS TO WHOM THESE PRESENTS SHALL COME:

Be it known, that I, CHARLES S. CHAFFEE, of East Cambridge, in the county of Middlesex and State of Massachusetts, have invented or produced an ornamental design for Tumblers, Goblets, &c.; and I do hereby declare the same to be fully represented in the accompanying drawings, of which—

Figures 1 and 2 denote side elevations of a tumbler, having the main parts of my design applied to it.

Figure 3 is an elevation, showing the other part of my design.

My said design consists in part of a shield formed in bas-relief, and ornamented with stars and stripes, arranged as seen in figure 1, the same being placed on one side of the tumbler.

It further consists of a flag-staff, (mounted with a battle-axe,) bearing the American flag, with the stars and stripes disposed as seen in figure 2; and, moreover, between the two I arrange a gun, as seen in figure 3.

I claim the said design, as above described, and as represented in the accompanying drawings.

CHARLES S. CHAFFEE.
